INVENTOR.

UNITED STATES PATENT OFFICE.

FREDERIC A. MORSE, OF PAWTUCKET, RHODE ISLAND.

LAMP.

SPECIFICATION forming part of Letters Patent No. 591,417, dated October 12, 1897.

Application filed September 18, 1896. Serial No. 606,220. (No model.)

To all whom it may concern:

Be it known that I, FREDERIC A. MORSE, a citizen of the United States, residing at Pawtucket, in the county of Providence and State of Rhode Island, have invented certain new and useful Improvements in Lamps; and I do declare the following to be a full, clear, and exact description of the invention, such as will enable others skilled in the art to which it applies to make and use the same, reference being had to the accompanying drawings, and to the letters of reference marked thereon, which form a part of this specification.

My invention relates to improvements in central-draft lamps in which is used my improved automatic liquid-indicator for which Letters Patent of the United States were granted to me April 28, 1896, No. 559,061; and the object of my invention is to provide a lamp in which a wick which has been partially unraveled at the lower end may be used without said wick interfering with the action of my indicator.

My invention consists, essentially, of a partly-cylindrical shield attached to the bottom of the lamp close to the central-draft tube, and which shield extends parallel with the tube upwardly into the body of the lamp and so adjusted as to leave an annular space between the shield and the central-draft tube of the lamp, so that the wick may be easily moved up and down in said space.

My invention is set forth clearly in the accompanying drawings, in which—

Figure 1 is a vertical section of the lamp, showing my automatic liquid-indicator in position, the wick and shield being at the right of the indicator, as shown. Fig. 2 is a vertical view of the wick. Fig. 3 is a perspective of the shield, and Fig. 4 a cross-section of the wick and shield through the line xx of Fig. 1.

The same letters refer to the same parts throughout the various drawings.

Where an ordinary wick is used, there is no need of my device, but many wick-makers ravel out the lower end of the wick ostensibly for the purpose of increasing its capillary power. This raveled lower end makes

a wide surface at the bottom of the wick, 50 which would ordinarily interfere with the operation of my indicator by becoming entangled with some of the movable parts thereof. In order to adapt my indicator to the use of this wick, I have devised the 55 shield which is the subject of this invention.

In Fig. 1, A is a central-draft lamp; D c d, my automatic indicator; B, the wick, and C e the shield. The wick B is raveled at its lower edge, as seen at a in Figs. 1, 2, and 4.

Fig. 3 shows the shield in detail, flanged at the bottom at b and flaring outward at the top, as shown at e in Figs. 3 and 1, so as to admit the wick easily into the space between the shield and the central tube of the lamp.

Fig. 4 is a section through xx of Fig. 1, showing the central tube, the wick, and the shield in section.

The shield is soldered or otherwise fixed to the bottom of the lamp and does not impair 70 the capillarity of the wick or in any way impede its movement, but does effectually prevent the ravelings from catching in the indicator.

Having now described my invention, what 75 I claim, and desire to secure by Letters Patent, is—

1. A center draft for lamps, combined with a short curved shield, provided at its lower edge with a flange b, and which shield is secured to the bottom of the lamp close to the central-draft tube, and extends parallel with the tube upwardly into the body of the lamp, substantially as shown.

2. In a center-draft lamp, a short curved 85 shield which is secured to the bottom of the lamp-body and extends vertically therein parallel with the center-draft tube, there being sufficient space between the draft-tube and the shield to allow the lower edge of the wick 90 to pass down between them, substantially as shown.

In testimony whereof I affix my signature in presence of two witnesses.

FREDERIC A. MORSE.

Witnesses:

ROSE E. DORRINGTON,
LELLAN J. TUCK.
